GIRDLE

Henry M. Herbener, Thomasville, Ga.

Application May 25, 1950, Serial No. 164,213

6 Claims. (Cl. 2—258)

1

My invention relates to girdles or like garments and to resilient means for holding a portion of the garment raised or in proper place upon the user.

An important object of the invention is to provide resilient means which will properly support the upper portion of the girdle, will retain the adjacent portion of the girdle close to the body of the wearer, and has a high degree of flexing action to permit of the bending or stooping of the body, without discomfort to the user.

A further object of the invention is to provide a supporting element which is light, simple and compact and will promote the comfort of the user.

In the accompanying drawings, forming a part of this application, and in which like numerals are employed to designate like parts throughout the same,

Figure 1 is a side elevation of a resilient supporting element embodying my invention, parts of the girdle being broken away, and parts in section,

Figure 2 is a vertical section through the supporting element, taken on line 2—2 of Figure 1,

Figure 3 is a side elevation of a second form of resilient supporting element,

Figure 4 is a vertical section through the supporting element taken on line 4—4 of Figure 3,

Figure 5 is a view similar to Figure 3, showing a further modified form of resilient supporting element,

Figure 6 is a vertical section through the supporting element taken on line 6—6 of Figure 5.

In Figures 1 and 2, I have shown a resilient device 41 to be applied to the front panel 26 of a girdle, to hold the front panel raised and in proper place upon the user, without discomfort. The panel 26 used in connection with the device 41 is vertically non-elastic. This resilient supporting element is designated by the numeral 41, and is formed of resilient sheet metal or like material. This resilient element comprises an upper head 42 and a lower head 43. The upper head 42 is horizontally arranged and provides a long bearing surface 44 and the head 43 is horizontal and provides a long bearing surface 45. The resilient supporting element 41 is integral and includes vertical strips 46 and 47, extending from the longitudinal centers of the heads 42 and 43 respectively. At their inner ends, the vertical strips 46 and 47 are integral with the longitudinal center of a horizontal strip 48 or torsional element. This horizontal torsional element or strip has vertically spaced longitudinal slits or slots 49, forming horizontal arms 50 and a filler section or web 51, which prevents the passage of flesh between

the horizontal arms 50. The arms 50 have a torsional action, corresponding to the U-shaped portions 30'.

The resilient supporting element 41 is applied to the upper portion of the front panel 26, between this panel and the outer layer 27, and the supporting element is held centered by line or lines of stitching 52, connecting elements 26 and 27. The top head 42 bears against the folded edge 28 of the front panel, while the bottom head 43 bears against the line of stitching 52.

This resilient supporting element will retain the upper edge of the panel 26 raised, and the upper edge of the panel may be bent or swung forwardly, the head 42 swinging forwardly and downwardly toward the head 43, and this swinging movement is rendered possible by the resilient action of the strips 46 and 47 and the torsional action of arms 50, which are resilient. When pressure is removed from the top of the panel, the supporting element 41 returns such top to the raised position.

In Figures 3 and 4, I have shown a further modified form of resilient supporting element. In this form of the invention the strips 46 and 47 are integrally secured to the longitudinal centers of horizontal strips or torsional elements 53 and 54. These torsional elements have longitudinal slits or slots 55, forming horizontal torsional arms 56. The inner arms 56 of the two torsional elements are connected by a web 57, at the longitudinal center of the same, forming slots 58.

The resilient supporting element shown in Figures 3 and 4 is applied to the front panel in the same manner as explained in connection with the supporting element 41 of Figure 1, and the same operation occurs. All other parts of the device remain identical with those shown and described in Figures 1 and 2.

In Figures 5 and 6, I have shown a further modification of the resilient supporting device wherein the vertical strips 46 and 47 are formed integral with horizontal strips or torsional elements 59, at their longitudinal centers. Each torsional element 59 has a pair of longitudinal slits or slots 60, forming horizontal resilient torsional arms 61, and a filler strip 62. The inner sides of the torsional elements 59 are connected at their longitudinal centers by a strip or web 63, forming slots 64. The entire device is integral and is otherwise identical with that shown and described in Figures 1 and 2. The supporting element of Figure 5 is applied to the front panel in the same manner as indicated in connection with the supporting element 41, Figure 1, and the operation is substantially the same.

It is to be understood that the forms of my invention herewith shown and described are to be taken as preferred examples of the same and that various changes in the shape, size, arrangement of parts may be resorted to without departing from the spirit of my invention or the scope of the subjoined claims.

Having thus described my invention, I claim:

1. A resilient supporting element to be applied to a girdle or like garment to hold the same in position upon the user, said element being formed from resilient sheet metal and including an upstanding strip provided near its top and bottom with generally horizontal heads, each head extending in opposite directions beyond the upstanding strip, and substantially horizontal upper and lower torsional arms, operatively carried by the upstanding strip, each torsional arm having its opposite ends extending beyond the upstanding strip, the opposite ends of each torsional arm being connected with the corresponding ends of the other torsional arm.

2. A resilient supporting element to be applied to a garment for holding the garment in position upon the user, said element comprising an upstanding resilient body portion having upper and lower ends, and a generally horizontal resilient torsional strip substantially rigidly secured to the body portion near its longitudinal center and remote from the upper and lower ends, said torsional strip extending outwardly beyond the side edges of the upstanding body portion, said torsional strip having spaced narrow openings formed therein, each opening extending throughout the major portion of the length of the torsional strip and having its opposite ends terminating short of and adjacent to the opposite ends of the torsional strip, the torsional strip including a filler strip arranged between the narrow openings and having its opposite ends secured to the opposite ends of the torsional strip.

3. A resilient supporting element to be applied to a garment for holding the garment in position upon the user, said element comprising an upstanding resilient body portion having upper and lower ends, and generally horizontal resilient torsional strips operatively secured to the body portion near its longitudinal center and remote from the upper and lower ends, said torsional strips being separated by narrow openings, each torsional strip extending outwardly beyond the side edges of the upstanding body portion, each torsional strip having spaced narrow openings formed therein, each opening extending throughout the major portion of the length of the torsional strip and having its opposite ends terminating short of and adjacent to the opposite ends of the torsional strip, each torsional strip including a filler strip arranged between the narrow openings of the torsional strip and having its opposite ends secured to the opposite ends of the torsional strip.

4. A unitary resilient supporting element to be applied to a girdle or like garment to hold the same in position upon the user, said element being formed of sheet metal and including an upstanding strip, upper and lower heads carried by the strip, each head extending for substantial distances beyond the edges of the upstanding strip, and a generally horizontal resilient torsional strip formed integral with the inter-

mediate portion of the upstanding strip and extending for substantial distances beyond the edges of the upstanding strip, said torsional strip having a longitudinal opening extending throughout the major portion of its length and terminating adjacent to and short of the opposite ends of said torsional strip.

5. A resilient supporting element to be applied to a girdle or like garment to hold the same in position upon the user, said element being unitary and formed from resilient sheet metal and including upstanding strip sections provided near their outer ends with generally horizontal heads, each head extending in opposite directions beyond the adjacent upstanding strip section, and a substantially horizontal torsional strip arranged between and formed integral with the inner ends of the upstanding strip sections and having its opposite ends extending beyond the upstanding strip sections, the torsional strip having longitudinal opening means formed therein which terminate short of the opposite ends of the torsional strip, the opening means forming substantially horizontal torsional arms, each torsional arm being connected at its opposite ends with the corresponding opposite ends of the companion torsional arm.

6. A resilient supporting element to be applied to a girdle or like garment to hold the same in position upon the user, said element being unitary and formed from resilient sheet metal and including upstanding strip sections provided near their outer ends with generally horizontal heads, each head extending in opposite directions beyond the adjacent upstanding strip sections, and a plurality of substantially horizontal torsional strips arranged between and formed integral with the inner ends of the upstanding strip sections, each torsional strip having its opposite ends extending beyond the adjacent strip section, each torsional strip having a plurality of longitudinal slots terminating near and short of the opposite ends of such torsional strip, the slots of each torsional strip forming substantially horizontal torsional arms, the opposite ends of each torsional arm being connected with the corresponding opposite ends of the companion torsional arm, and an intermediate strip formed integral with the adjacent inner torsional arms of the torsional strips.
